UNITED STATES PATENT OFFICE.

JOHN A. CALDER, OF TORRINGTON, AND WILLIAM H. DAYTON, DECEASED, LATE OF TORRINGTON, CONNECTICUT; BY JAMES M. DAYTON, ADMINISTRATOR, OF SPRINGFIELD, MASSACHUSETTS, ASSIGNEES TO THE TORRINGTON COMPANY, OF TORRINGTON, CONNECTICUT, A CORPORATION OF CONNECTICUT.

NEEDLE-LATCH-RIVETING MACHINE.

Application filed December 6, 1918. Serial No. 265,541.

To all whom it may concern:

Be it known that we, JOHN A. CALDER, a citizen of the United States, residing at Torrington, Litchfield County, Connecticut, and JAMES M. DAYTON, of Springfield, Massachusetts, administrator of the estate of WILLIAM H. DAYTON, deceased, also a citizen of the United States, and late a resident of Torrington, Litchfield County, Connecticut, have invented certain new and useful Improvements in Needle-Latch-Riveting Machines, of which the following is a description, reference being had to the accompanying drawings, and to the figures of reference marked thereon.

The invention relates to new and useful improvements in needle latch riveting machines, and more particularly to the mechanism for operating the riveting members.

An object of the invention is to provide a riveting machine of the above character, wherein the riveting members are given rapidly a series of movements for upsetting or balling the rivet, and wherein the movements of the riveting members are suspended substantially during the time of the withdrawing and inserting of another needle for the riveting of the latch therein.

A further object of the invention is to provide a riveting machine wherein the rivet is upset at one station and the heads of the rivet are balled and seated in recesses in the side faces of the needle at another station.

These and other objects will in part be obvious and will in part be more fully disclosed.

In the drawings which show by way of illustration one embodiment of the invention—

Figure 1 is a view showing more or less diagrammatically, a latch needle having a latch in place and the wire inserted from which the rivet is to be formed;

Figure 2 is a similar view, but showing the completed rivet having the center thereof enlarged to form a bearing support for the latch and the heads of the rivets balled and seated in the recesses in the side faces of the needle;

Figure 3 is a view partly in section and partly in side elevation, showing one of the riveting devices;

Figure 4 is a perspective view of the riveting members and the immediate parts for supporting and operating the same;

Figure 5 is an enlarged detail, showing the adjustable pivot support for one of the riveting members;

Figure 6 is a view partly in section and partly in side elevation of the riveting members and showing particularly the manner of mounting the riveting hammers in the operating members therefor;

Figure 7 is an end view of the riveting members;

Figure 8 is a sectional view on the line 8—8 of Figure 6;

Figure 9 is a sectional view on the line 9—9 of Figure 6;

Figure 10 is a side view of the controlling bar which causes the riveting devices to be effective or ineffective;

Figure 11 is a similar view at right angles to that shown in Figure 10;

Figure 12 is a side view of the rotating head which carries the controlling means for the riveting devices;

Figure 13 is a view at right angles to that shown in Figure 12;

Figure 14 is an end view of the rotating head;

Figure 15 is a side view of the shiftable crank pin for operating the riveting devices;

Figure 16 is a top plan view of the same;

Figure 17 is a perspective view of the supporting and guiding posts for positioning the needle relative to the riveting devices;

Figure 18 is a view partly in plan and partly in section of the same;

Figure 19 is a view showing more or less diagrammatically, the two associated riveting devices, one for upsetting and the other for heading the rivet and the means for presenting the needle first to one riveting device and then to the other;

Figure 20 is an enlarged view partly in section and showing the operation of the upsetting devices;

Figure 21 is a similar view, but showing the operation of the rivet balling devices.

The invention consists broadly in a riveting mechanism having two riveting devices or hammers which are adapted to simultaneously impart blows to the rivet for upsetting and for heading the rivet. This riveting mechanism is controlled by certain devices, so that the riveting hammers are set into operation and caused to impart a series of blows to the rivet, after which the movement of the riveting hammers is caused to cease and the parts are so timed that the riveting hammers are in action only substantially during the time of the upsetting or heading of the rivet. This enables the riveting hammers to be very nicely adjusted and avoids all strain on the riveting hammers incident to the constant vibration of the same when there is no rivet in place to be operated upon. Means is also provided for adjusting the riveting members relative to each other, so that they may be brought into proper alinement and proper working position relative to each other in order to accomplish the desired result either in the upsetting or heading of the rivet.

In the riveting of a latch needle, it is desirable to bring about the upsetting of the rivet at one operation, or at one station, and the heading of the rivet at another station. To this end, two riveting mechanisms of a similar character are provided, one of which has riveting hammers, which are constructed and controlled so as to upset the rivet causing the central part of the rivet to bulge or enlarge, and the other set of riveting hammers are so constructed and operated as to finish the enlargement of the center of the rivet and to ball the heads of the rivet, seating the same well beneath the outer surfaces of the needle in recesses provided for the same. Automatic means is provided for presenting the needle first to one riveting mechanism and then the other.

The improved riveting machine and the manner of operating the same will be made clear by a detail reference to the drawings. In the Figures 1 and 2, there is shown a needle N, which is of the latch needle type, and inserted in the needle is a latch L. Along side of the latch is a paper shim, indicated at p. In Figure 1, the stock from which the rivet is formed is indicated at r and this stock is cut at the right length to form the rivet. It will be noted that the side walls of the needle are formed with recesses and, as clearly shown in Figure 2, in the final heading of the rivet, the ends thereof are balled and the edges of the ball-shaped head are carried well into the respective recesses.

The riveting machine includes a suitable supporting frame 3, on which is mounted an

endless carrier 4, provided with a series of chucks 5-5. These chucks are mounted on the endless carrier, so that they may be moved transversely thereof, and each chuck is provided with a suitable clamping means for clamping the needle. A controlling bar 6 serves as a means for moving the chucks forward to present the needles to the riveting station. The endless carrier moves in the direction of the arrow, indicated in Figure 19, and has a step by step movement in order to bring the chucks first to one riveting station and then the other. The upsetting riveting station is indicated at A, in this figure of the drawings, and the heading station is indicated at B. The riveting mechanisms at the two stations are exactly the same except for the construction of the head of the riveting hammers, and, therefore, only one of the riveting mechanisms has been illustrated and will be described in detail.

As the chuck moves forward at the riveting station, it brings the needle with the latch inserted and the rivet material in place into proper position relative to a supporting post 287, see Figures 17 and 18. Said supporting post is secured to the frame 3 of the machine and is provided with an adjustable arm 288, which is secured to the post by screws 289. This arm has an inclined ledge 290 and a vertical shoulder, which is also inclined, as indicated at 291. The purpose of these inclined parts is to direct the point of the needle so as to properly position the needle with the rivet therein for the riveting hammers to strike the same. Also, carried by the supporting post 287 are guide plates 292 and 293. The adjacent edges of these guide plates are slotted so as to form a recess 294 for the point of the needle to enter. These guide plates are pivoted to the post 287 and are held on their pivots by an overlapping arm 295. A spring 296 holds the plates together. The recess 294 is tapered, as clearly indicated in dotted lines in Figure 18, and this enables the needle point to enter between the guide plates which centers the needle for the riveting operation. The above structure is shown in an organized machine and described more in detail in the patent granted William H. Dayton, November 14, 1921, No. 1,381,810.

The riveting hammer 297 is carried by a lever 299, which is pivoted at 300 to a supporting block 301, carried by the frame 3. The riveting hammer 298 is carried by a lever 302, which is pivoted at 303 to the block 301. The pivot 303 is formed with an eccentric section 304 around which the lever 302 swings. By adjusting the pivot 303, the fulcrum point of the lever 302 may be shifted and this will change the working position of the hammer 298.

The lever 299 is provided with a pivotally mounted head 333, in which the hammer 297 is clamped by the screws 338. A clamping plate 337 holds the hammer and the screws 5 passing through this clamping plate cause the same to grip the hammer and firmly hold the same, see Figure 9 of the drawings. This head 333 is mounted to swing about a pivot point 334. Extending laterally from 10 the lever 299 are shoulders 336. Threaded into the head 333 are screws 335, which are adapted to bear respectively against the shoulders 336. It will readily be seen that, by loosening one of the screws 335 and tightening the other, the pivot head 333 may be 15 swung to the right or left about the pivot point 334. This provides for a lateral adjustment of the upper riveting hammer 297 and enables the riveting hammers to be 20 quickly brought into proper alignment. A screw 306 is threaded into the upper end of the head and serves as an abutment for the hammer 297. By loosening the screws 338, and turning the screw 306, the vertical position 25 of the upper hammer may be readily adjusted and then the screws 338 turned in to hold the hammer in an adjusted position.

The lower hammer 298 is clamped to the lever 302 by a clamping screw 307. The end 30 of the lever is split and the clamping screw draws the split ends together, thus firmly clamping the lower hammer. This lower hammer rests against an adjustable abutment 308, which provides the means for vertically adjusting the lower hammer. As 35 above noted, the position of the lower lever 302 can also be adjusted by shifting the fulcrum thereof.

The levers 299 and 302 are moved toward 40 and from each other by a bar 309, which slides in the block 301. This bar is formed with a head 310. A link 311 is pivoted at its lower end to this head and at its upper end to the lever 299. A link 312 is pivoted 45 at its upper end to this head and at its lower end to the lever 302. These links are set so as to move from alignment to a position at angles to a line passing through their pivotal connections with the head, so that, 50 as the bar 309 reciprocates, the levers 299 and 302 will be rapidly moved toward and from each other. Buffer springs 313 may be used in connection with the levers carrying the hammers. The bar 309 is reciprocated by means of a link 314. This link is 55 connected to a crank pin 315, rigidly carried by a block 316. The block 316 is mounted to slide radially on a rotating sleeve or shaft 317, carrying a head 318, formed with a slot 319 to receive this block 316. The sleeve 317 carries a beveled gear 320, which meshes with a beveled gear 321 on a short shaft carrying a belt wheel 322. This belt wheel is driven by a belt 323, 60 which may be operated from an overhead

shaft. The sleeve 317 is journaled so as to rotate in a suitable bracket 324. Extending centrally through this sleeve is a rod 325, which has an inclined end 326, adapted to engage a similar shaped recess 70 327 formed in the block 316. This rod 325 is capable of endwise movement in the sleeve and is moved by a rock lever 328 which is pivoted at 329 to a bracket arm 330. This rock lever carries a roller 331, which engages a cam 332, mounted on the shaft 8a. The crank pin 315 is positioned on the block 316 and when the rod is in the position shown in Figure 3, this crank pin is concentric with the axis of the rotating sleeve 80 and as a consequence, no movement will be imparted to the link 314 or to the riveting hammers. If, however, the rod 325 be raised, the inclined end 326 thereof will force the block 316 radially of the sleeve, 85 so as to set the crank pin off center and this results at once in an endwise vibration of the link 314, which in turn moves the bar 309 back and forth endwise and this will rapidly vibrate the hammers so as to 90 bring about the upsetting of the rivet, which, of course, is placed directly between the hammers. By this means the riveting hammers may be controlled so as to be actuated only when there is a rivet between 95 the same, thus greatly reducing the wear of the riveting hammers and maintaining a proper throw to bring about just the desired amount of upsetting of the rivet. Co-operating with the crank pin 315 is a rotatable table 315a which affords a means for holding the link on the crank and permitting the adjustment of the crank to eccentric position. By shifting the pivot pin 303, the fulcrum point of the lever 302 may 100 105 be varied so as to vary the working position of the hammer carried by said lever 302.

In Figure 20, there is shown the effect of the upsetting of the riveting mechanism. The riveting hammers are provided with flat heads and these riveting hammers first operate to center the rivet so that it projects an equal distance above and below the needle and then it causes a bulge of the rivet at the center thereof and a slight enlargement or upsetting of the head. After the rivet has been operated upon in the manner above stated, so as to bring about an upsetting of the rivet, then the chuck moves to the next riveting station where 110 115 120 the riveting hammers are shaped so as to ball the ends of the rivet.

In Figure 21 of the drawings, the riveting hammers are shown as having recesses in their faces and these hammers are shaped so as to round or ball the head of the rivet and seat the balled heads in the recesses in the sides of the needles. The chuck presents the needle with the rivet therein first to the upsetting station where the rivet is 125 130

upset. After this operation is completed, the chuck withdraws the needle, the carrier moves forward and then the chuck presents the needle to the next riveting station. The cam which controls the effective operation of the riveting members is so shaped as to cause the riveting hammers to operate only when the rivet is between the hammers and when the riveting hammers would become effective for upsetting or balling the rivet. During the time when the needle is being retracted and presented to the next station, the riveting mechanism is rendered ineffective by means above described. Of course, it is understood that the needles are presented one after another in succession, to first one riveting mechanism and then the other.

From the above, it will be apparent that a riveting machine is provided wherein the rivet is upset at one station and balled or headed at another station, and these riveting mechanisms at each station are so operated as to be ineffective during the time when the needle is being conveyed from one station to another. Furthermore, the riveting mechanisms are so constructed that the working position of the riveting members may be rapidly adjusted and the position of the hammers on the operating levers may also be quickly adjusted so as to bring the same into proper alinement and also into proper working relation to each other.

It is obvious that minor changes in the details of construction and the arrangement of parts may be made without departing from the spirit of the invention, as set forth in the appended claims.

Having thus described the invention what is claimed as new and desired to secure by Letters Patent, is:

1. A riveting machine including in combination, riveting hammers, an operating lever for each hammer, means for rapidly vibrating said levers and for automatically suspending the vibrations thereof so as to facilitate the placing of the rivet between the hammers.

2. A riveting mechanism including in combination, riveting hammers, an operating lever for each hammer, a reciprocating head, a link for connecting each lever to said head, said links being disposed so as to move toward and from alinement for operating the levers, one of said levers being mounted on an eccentric support and adapted to be shifted for bringing the rivet and hammers into proper alinement.

3. A riveting mechanism including in combination, riveting hammers, an operating lever for each hammer, a link for connecting each lever to said head, said links being disposed so as to move toward and from alinement for operating the levers, and

means for reciprocating said head including devices whereby the reciprocations of the head may be suspended periodically to permit the insertion and removal of the work between the riveting hammers.

4. A riveting mechanism including in combination, riveting hammers, a pivoted lever for each hammer, a head movable between said levers, a link connecting each lever with said head, said links being disposed so as to move toward and from alinement for positively reciprocating the levers, and buffer springs for cushioning the levers on their movement toward each other.

5. A riveting mechanism including in combination, riveting hammers, a pivoted lever for each hammer, a reciprocating member located between the said levers, a link pivotally connecting each lever to said reciprocating member, said links being so disposed as to move toward and from alinement for reciprocating the levers, means for reciprocating said member including devices for automatically suspending said reciprocations periodically to aid in the insertion and removal of the work.

6. A riveting mechanism including in combination, riveting hammers, a pivoted lever for each hammer, a reciprocating head between the levers, a link connecting said reciprocating head with each lever, said links being disposed so as to move toward and from alinement for reciprocating said levers, a rotating shaft, a crank carried thereby and connected to said head for reciprocating the same, means for shifting the crank from a position in line with the axis of the shaft to a position eccentric thereto, whereby the riveting members are rendered effective or ineffective.

7. A riveting mechanism including in combination, riveting hammers, a pivoted lever for each hammer, a reciprocating head between the levers, a link connecting said reciprocating head with each lever, said links being disposed so as to move toward and from alinement for reciprocating said levers, a rotating shaft, a crank carried thereby and connected to said head for reciprocating the same, a rod sliding vertically of the shaft and connected to said crank for shifting the same radially of the shaft, and a rotating cam for shifting said rod whereby the riveting hammers are automatically suspended periodically to facilitate the insertion and removal of the work.

8. A riveting machine including in combination, riveting hammers, an operating lever for one of said hammers, a pivoted head mounted on the lever and supporting the hammer, means for clamping the hammer to the head, means for shifting the pivoted head and clamping the same in position, and an adjustable abutment carried by the head for said hammer.

9. A riveting machine including in combination, riveting members, a reciprocating member for operating said riveting members, a rotating shaft, a crank adjustable 5 radially of the rotating shaft, a rod extending lengthwise of the shaft and having a cam end for moving the crank from the position in line with the axis of the shaft to a position eccentric thereto, means for rotating the same, and means for reciprocating the rod.
- In testimony whereof, we affix our signatures.

JOHN A. CALDER.

JAMES M. DAYTON,

*Administrator of the Estate of William H.
Dayton, Deceased.*
